Primary Examiner — Jennifer L Watkins(74) *Attorney, Agent, or Firm* — Finnegan, Henderson, Farabow, Garrett & Dunner LLP**CLAIM**

The ornamental design for footwear, as shown and described.

DESCRIPTION

FIG. 1 is a front right perspective view of the footwear showing our new design;

FIG. 2 is a front top perspective view thereof;

FIG. 3 is back elevation view thereof;

FIG. 4 is a top plan view thereof;

FIG. 5 is a left side elevation view thereof; and,

FIG. 6 is a right side elevation view thereof.

The broken lines of uneven length represent the boundary of the claimed design and form no part of the claimed design. The area on the bottom of the footwear outside the broken lines shown in lighter tone forms no part of the claimed design.

1 Claim, 6 Drawing Sheets(56)
